UNITED STATES PATENT OFFICE

RUSSELL A. PICKENS, OF FAIR LAWN, NEW JERSEY, ASSIGNOR TO SERVEL INC., OF NEW YORK, N. Y., A CORPORATION OF DELAWARE

COMBINATION DRINKING WATER AND ROOM COOLER

Application filed May 7, 1930. Serial No. 450,368.

This invention relates to a cooler designed for cooling drinking water and the air within a room.

It is an object of the invention to provide a combination cooler of this character of compact construction which will not occupy more space than is required by a cooler designed to perform one of these functions and at the same time to provide a room and water cooler which is simple and inexpensive to manufacture.

The invention will first be hereinafter more particularly described with reference to the accompanying drawings which form a part of this application and later pointed out in the claims at the end of the description.

In said drawings:

Fig. 1 is a front elevation illustrating one application of the invention;

Fig. 2 is a vertical section; and

Fig. 3 is a horizontal section.

Referring to said drawings in which the same reference characters are used to denote corresponding parts throughout the several views, 10 indicates a cabinet having a lower machine compartment 11 and an upper refrigerating compartment 12 for the reception of cooling coils and a fan hereinafter more particularly described.

30 The upper compartment is surrounded by a wall 13 of insulating material and has mounted therein a water cooling coil 15 located in a narrow tank 16 centrally of said compartment and between chilling sections

35 14. The chilling sections are spaced to provide between the same warm air ducts or flues for the passage of air to be chilled, such air being admitted through the front of the lower compartment, which is provided with a reticulated screen or net work S. A deflector plate D preferably of sheet metal or the like material has its lower edge disposed at the lower edge of the front opening or 40 screen S and extends upwardly and rearwardly over the compressor and motor in order to prevent heating of the air which enters the cabinet by such motor and compressor.

45 The upper surface of the refrigerating compartment is inclined and is provided with

a grilled opening 17 through which air may be expelled into the atmosphere of the room by the fan 18.

Beneath the chilling tank 16 in which the water coil is mounted, is located a wall of insulating material 19 to prevent the tank from being heated by warm air entering the cooler and baffles 20 are disposed at each side of the member 19 to direct the warm air away from said tank. The water coil 15 has a connection 21 with a source of supply and a connection 22 with a drinking fountain nozzle 23, a valve 24 being inserted for controlling the operation of such drinking fountain. A waste pipe 25 serves to carry away water not consumed at the fountain and may be connected with a waste or other discharge line, not shown.

55 A pressure line P connects the compressor of the machine 27 with the chilling sections 14 and a suction or return line R is also connected to such sections; an expansion valve 26 is inserted in the pressure line for a well known purpose.

60 The tank 16 is adapted to contain a water bath around the coil 15 through which the drinking water is adapted to pass. This water bath will be cooled by the chilling sections 14 and will maintain the drinking water within the coil 15 at the proper temperature. The water bath also will serve to prevent the freezing of the drinking water within the coil 15 and provide a reserve refrigerating capacity or prolong the refrigerating effect so that water within the coil will 65 always remain cold and in a liquid state.

66 In operation, the compressor of the machine 27 forces compressed gasified refrigerant through the pipe line P to the condenser C where it is condensed and such condensed liquid passes through the expansion valve 26 and expands in the chilling sections 14 cooling them. The liquid returns through the return line R to the compressor. At the same 70 time the fan 18 draws in and causes air to circulate through the device, the air entering through the grilled opening S in the lower compartment and being caused to pass 75 upwardly over the shield D between and 80 upwardly over the shield D between and 85 upwardly over the shield D between and 90 upwardly over the shield D between and 95 upwardly over the shield D between and 100

around the chilling sections and is expelled through the grilled opening 17. The fan 18 is connected to operate with the motor for the compressor so that when one is shut down 5 the other will also be shut down. The condenser C is of the water cooled type.

While I have shown cooling sections of one type, obviously they may be of another type if preferred, for example, "Murray".

10 It will be readily apparent that my device is particularly adapted for use where it is an advantage to have both drinking water and means for maintaining the air within the room at a comfortable temperature, and 15 therefore the invention is not limited to the use of the device merely in one embodiment, but various changes may be made without departing from the spirit of the invention.

I claim:

20 1. A combined water and room cooler comprising a cabinet, a plurality of chilling sections in said cabinet defining air passages therebetween, a tank located between certain of said chilling sections and a water 25 cooling coil located in said tank.

2. A combined room and water cooler comprising a cabinet having upper and lower compartments, a refrigerating unit in the lower compartment, a plurality of chilling 30 sections supported in the upper compartment in spaced relation and providing vertical flues, means for circulating a refrigerating medium through the chilling sections, a tank intermediate the chilling sections, a cooling coil in said tank, and a drinking fountain connected with said cooling coil.

3. A combined room and water cooler comprising a cabinet having upper and lower compartments, a refrigerating unit in the lower compartment, a plurality of chilling sections supported in the upper compartment in spaced relation and providing vertical flues, means for circulating a refrigerating medium through the chilling sections, a tank 35 intermediate the chilling sections, a cooling coil in said tank, a drinking fountain connected with said cooling coil, and means for drawing air into and discharging air from said upper compartment.

40 4. A combined room and water cooler comprising a water cooling coil, a tank housing said coil adapted to contain a cooling solution, a plurality of chilling sections disposed about said tank and defining warm air flues 45 between the chilling sections, and means for creating a draft of air past said chilling sections.

45 5. A combined room and water cooler comprising a cabinet having inlet and discharge openings, a plurality of chilling sections in said cabinet supported in a manner to form flues therebetween, means for supplying refrigerant to said chilling sections, a tank disposed among the chilling sections, a pipe coil located in said tank, means for admitting and

discharging water from said cooling coil, and means for creating a draft of air through said cabinet.

6. A combined room and water cooler comprising a submerged water cooling coil, chilling section beside the water cooling coil, warm air flues between said chilling sections, and means for insulating the bottom of the water coil from warm air coming into the cabinet. 70

7. A device of the character described comprising a compartment to be refrigerated, a plurality of chilling units in said compartment connected in series, a water coil disposed among said chilling units having one end adapted for connection to a source of supply 80 and its other end provided with a bubbler, a tank enclosing said coil and adapted to maintain a body of liquid about the coil to prevent freezing of the water in the coil and to form a hold-over. 85

8. A device of the character described comprising an insulated compartment to be refrigerated, an air inlet passage in the lower portion and an air outlet passage from the upper portion of said compartment, a plurality of chilling units in said compartment connected in series, a water coil disposed among said chilling units having one end adapted for connection to a source of supply 90 and its other end provided with a bubbler, a tank enclosing said coil and adapted to maintain a body of liquid about the coil to prevent freezing of the water in the coil and to form a hold-over, and a fan in said compartment for forcing air through the compartment. 95

9. A device of the class described comprising a cabinet having upper and lower compartments, a refrigerating unit in the lower compartment, a water tank in the upper compartment, a water coil in said tank having one end for connection to a source of supply and its other end provided with a bubbler, a plurality of chilling units disposed about said tank in said upper compartment in a 100 manner to refrigerate the tank, insulating material beneath the bottom of said tank with passages for air between the lower and upper compartments at each side of the same, an inlet for air into the lower compartment, and 105 an outlet for air from the upper compartment. 110

10. A device of the class described comprising a cabinet having upper and lower compartments, a refrigerating unit in the lower compartment, a water tank in the upper compartment, a water coil in said tank having one end for connection to a source of supply 115 and its other end provided with a bubbler, a plurality of chilling units disposed about said tank in said upper compartment in a 120 manner to refrigerate the tank, insulating material beneath the bottom of said tank with passages for air between the lower and upper compartments at each side of the same, an inlet for air into the lower compartment, and 125 an outlet for air from the upper compartment. 130

outlet for air from the upper compartment, and a fan in the upper compartment above said chilling units for drawing air into the cabinet through the lower opening and discharging air from the cabinet through the upper opening.

In testimony whereof I affix my signature.

RUSSELL A. PICKENS.
